ARTICLE HOLDER FOR SERVICE TRAYS AND STANDS

John David Ingram, Dallas, Tex.

Application June 22, 1933, Serial No. 677,128

2 Claims. (Cl. 65—65)

The present invention relates to article holders adapted particularly for use in connection with curb service of foods and beverages.

It has become quite a common practice today for road-side stands and eating places to serve their automobile customers at the curb or elsewhere while said customers remain in their automobiles. The food and drink are usually served upon trays and in the course of carrying these trays it frequently happens that the liquids are spilled. If napkins, straws, and other like service equipment are provided, as is quite the custom, they are damaged or soiled, making the service unattractive. To avoid this, waiters and waitresses sometimes carry the equipment in their pockets or attempt to hold them in their hands, a practice which is considered anything but sanitary. At other times, the napkins, straws, spoons, etc., are placed in a tumbler on the tray, but this is also very unsatisfactory.

It is the object of this invention to overcome these defects by providing a convenient holder in which separate receptacles are adapted to contain the respective articles so that one or more of such articles may be displaced therefrom as the food and drink are served from the tray.

More specifically, it is a further object to provide a combination holder having means adapted for application to a service tray so as to prevent accidental displacement or overturning of the holder device.

Another object resides in the provision of a tray engaging element which functions also as a connector for the receptacles and by means of which a unitary holder is produced capable of positive connection with the tray or of being stood upon the surface thereof, as may be desired.

Other and further objects and advantages of the invention will be hereinafter set forth and the novel features thereof defined by the appended claims.

In the drawings:—

Fig. 1 is a perspective view of one form of my invention in position upon the edge of a service tray;

Fig. 2 is a top plan view;

Fig. 3 is a vertical sectional view on the line 3—3 of Fig. 2;

Fig. 4 is a side elevation showing the holder device standing upon a flat surface instead of being attached to a tray;

Fig. 5 is a transverse sectional view on the line 5—5 of Fig. 2;

Fig. 6 is a front elevation of a modified form of the invention;

Fig. 7 is a side view of the same showing the device seated in a tray but not positively connected thereto;

Fig. 8 is a front elevation of a still further modification of the invention; and

Fig. 9 is a vertical sectional view through the form shown in Fig. 8.

Like reference characters designate corresponding parts in the several figures of the drawings.

Referring to the drawings and specifically describing that form of the invention shown in Figs. 1 to 5, 1 designates an article receptacle, in this instance a straw holder, cylindrical in cross section and open at the top to enable the removal of straws therefrom. For the major portion of its length this tubular receptacle has its sides cut away, as indicated at 2, the side opening thus formed tapering at each end to a narrow slot 3. While ready access is afforded to the straws by this form of opening, the slots 3 tend to restrict the number which may be removed at one time to a minimum of one or two.

A second open front receptacle 4, for holding napkins in a folded form, is associated with the straw holder 1, the sides 5 of this napkin receptacle being in the nature of spaced guide flanges. The two receptacles described are connected together by means of the fastening members 6 passing through the flanges 5. This arrangement rigidifies the holder 4 and makes a much stronger unit. To this unit preferably a supporting plate 7 is connected, as by means of fastening members 8. This plate is of spring metal and extends at one end beneath the receptacle 4, as shown in Fig. 3; while at its other end it is bent at an angle and rebent upon itself to form a strong attaching clip 9 by means of which to apply the unit to the edge flange of a service tray 10. The rear end of the plate 7 referred to, by cooperation with the bottom of the receptacle 4, tends to resist bending of the plate from constantly attaching the clip to trays and otherwise this plate serves as a supporting stand for holding the device in the position shown in Fig. 4 when placed upon a tray, a table, or other flat surface. This attaching plate makes the unit much stronger in that its connection to the receptacles assists the connection between the receptacle 1 and the receptacle 4.

The supporting plate 7 may be omitted, however, as shown in Figs. 6 and 7, and in this instance, by reason of the coincidence of the bottom plane of the two receptacles, the unit will stand in a substantially vertical position as shown. By virtue of the relatively long receptacle 1 a

wide surface contact of the bottoms of the two receptacles affords a stable holder.

Passing now to that form of the invention shown in Figs. 6 and 7 it will be observed that this differs only from the form shown in Figs. 1 to 5 by the omission of the connecting plate and clip 7, 9. The holder device in this form is just as effective for holding napkins and straws but naturally it occupies a portion of the surface of the tray and to this extent prevents the full use of this surface for the food and drink. It is for this reason that the form shown in Fig. 1 wherein the device is attached to the edge of the tray, is considered preferable.

15 In the form of the invention shown in Figs. 8 and 9 the straw holding container 1a is disposed in vertical position and attached to the rear of the napkin holding receptacle 4a by means of the fastening member 4b and to the bottom of said receptacle by the clip plate 7a through the fastening means 7b. The straw receptacle preferably contains the straw ejector comprising the stem 11, the bottom disc 12 upon which the straws rest and the top disc 13 which constitutes 20 a cover for the open-ended receptacle. The end of the stem is provided with a finger-piece 14 by means of which the ejector is elevated to render the straws projected from the mouth of the receptacle accessible for displacement. The plate 7a referred to is provided with the friction clip 9a as in the first form described. It will be obvious that this form of the invention may readily be attached to the trays and is much narrower than the forms shown in the other figures of the drawings.

Each of these devices is preferably made of chrome nickel finished metal or thin brass, copper, aluminum, or the like. The sizes and shapes of the respective receptacles may be modified according to the articles which are to be held thereby and it is to be understood that I do not wish to be restricted to the specific forms herein disclosed for this reason.

Having thus described my invention what I claim as new and desire to secure by Letters Patent is:

1. A unitary article holder comprising a cylindrical receptacle, a napkin holder at one side thereof, and a supporting plate connecting said receptacle and holder, said plate having an angularly bent leg forming a rest to dispose the holder in substantially upright position when placed upon a supporting surface, said leg having an integral tray gripping element on its upper side for attaching the holder to trays.

2. An article holding device of the class described, comprising a receptacle having an open top for removing the contents thereof, a second receptacle disposed with its bottom in substantially the same plane as the first receptacle to provide a relatively wide supporting surface contact when the bottoms of said receptacles are disposed upon a plane support, said second receptacle having an open front wall formed with spaced guide flanges, and fastening means for 105 clamping the side surface of the first receptacle against the front face of the flanges of the second whereby to connect the receptacles together to form a holder unit.
